TORQUE INDICATING WRENCH

August Brunelle, Ridgewood, N. J., assignor to
Wright Aeronautical Corporation, a corporation
of New York

Application September 2, 1939, Serial No. 293,222

5 Claims. (Cl. 177—311)

This invention relates to wrenches of the type which are capable of registering the torque applied thereby and a particular object is to provide means by which the application of a preset torque is indicated to the operator through his tactile sense, rather than requiring his visual observation of meters or dials according to conventional practice. By the use of a tactile indicator, no limitation is imposed on proper torque measurement due to lighting conditions or accessibility of the parts being worked upon, and indication will definitely be conveyed to the operator without undue concentration by him on just one phase of the wrench operation, thus allowing for more expeditious work with increased accuracy. A further object is to provide means in a torque indicating wrench by which the nut or other part being worked upon will be firmly seated at the desired torque by application of vibrating forces thereto, such vibration being applied only at the desired torque whereby fatigue of the operator is minimized. Still another object is to provide a torque metering wrench of rugged and simple design which will be adaptable to use over a large range of bolt and nut sizes.

In general, torque metering or indicating wrenches are useful in the automotive and aircraft arts, and in others, where mechanisms are highly developed and where it is desired to develop the strength of screw connections to the fullest extent. It is well known that loose screw connections are subject to failure and further loosening in machine assemblies, while too tight screw connections cause overstressing and failure of materials. Each screw size has an optimum tightness which is difficult of attainment without an adequate torque metering wrench. This invention provides a wrench which is as easy to use as an ordinary wrench, and which is reasonable in cost.

Additional objects of the invention will become apparent in reading the subjoined detailed description in connection with the drawing, in which

Fig. 1 is a plan of the wrench;

Fig. 2 is a longitudinal section on the line 2—2 of Fig. 1;

Fig. 3 is a section on the line 3—3 of Fig. 2;

Fig. 4 is a longitudinal section through part of the wrench on a plane normal to that on which Fig. 2 is taken, and

Fig. 5 is an enlarged section on the line 5—5 of Fig. 4.

The wrench comprises an end terminal 10 provided with a squared portion 11 over which the

components of socket wrench sets may be assembled, the terminal having a transverse hole in which a torque bar 12 is inserted, the latter being retained in the terminal by suitable means such as a set screw 13. The bar is preferably of spring steel, and may be any shape or of uniform section throughout its length. On the free end of the bar, a handle 14 is secured, the handle comprising a hollow, as at 15, and a knurled grip 16, the handle being slipped over the bar and pinned as at 17. A strip or plate 18, having substantial stiffness in the plane of action of the wrench, is secured to the terminal 10 by a screw 19 and pins 20, the latter securing the strip and terminal against relative rotation. At the free end of the strip 18, a laterally extended portion 21 is provided, the substantially arcuate edge 22 of which is calibrated to show applied torque. A guide 24, clamped to the bar 12, carries an adjustable grooved screw element 25 engaged over the edge of the portion 21 to prevent vertical displacement of the strip, and to adjust the contact points later described, this element also serving as an index against which the scale 25 marks on the strip may be observed.

The portion 21 is formed with a substantially arcuate slot 27 through which a pin 28 passes, the pin having flat sides to prevent turning in the slot, having a contact point at its lower end 30 of a diameter appropriate to embrace the torque tolerance permitted in operating on bolts or nuts, and having screw threads at its upper end. A nut 29 over an index tab 29' serves to secure the pin at any selected position along the slot 27. A second contact point 30 is clamped around the bar 12, insulated therefrom by a strip 31, the contacts 30 and 28 being engageable on torque application and bending of the bar 12 to close an electric circuit formed through the strip and bar and 40 through a wire 32 leading into the handle hollow 15 through appropriate drillings therein and in the element 24.

Within the handle is secured a ferrous core 34 by screws 35, a spring armature 36 being secured 45 between the core and handle and extending around the handle bore in clearance relation to carry a pole piece 37 and a tapping button 38. Solenoid windings 39 around the core 34 connect to the wire 32 and to one prong 40 secured in an insulating plate 41 adjacent the handle end, another prong 42 therein being connected to the bar 12 by a wire 43.

Preferably the solenoid is energized by low voltage alternating current through a transformer operating from a conventional lighting cir-

cuit, low voltage being used to avoid possibility of shocks to the operator. Alternately, the solenoid may be arranged as a buzzer operating on low voltage direct current, the tapping button comprising a make-and-break contact.

If the device be adapted for higher voltage, the wiring would preferably be insulated, in which case the bar 12 would comprise a tube through which wire 43 passes to the terminal 10 and thence along the strip 18 to the contact 28 10 which would be insulated from the wrench proper.

The tapping button is preferably active in the plane of action of the wrench. In operation the operator pulls upon the handle 14 and shortly contacts 28 and 30 engage to energize the solenoid 34—39, vibrating the handle to apprise the operator that the desired torque has been applied. The vibration imposed upon the wrench during application of torque within the deflection range embraced by the contacts 28, 30 also serves to 20 vibrate the nut or bolt worked upon into a firm seat with its coacting machine parts.

While I have described my invention in detail in its present preferred embodiment, it will be obvious to those skilled in the art, after understanding my invention, that various changes and modifications may be made therein without departing from the spirit or scope thereof. I aim in the appended claims to cover all such modifications and changes.

I claim:

1. A torque metering wrench comprising an elastic bar of uniform cross section, a terminal element embracing one end of the bar and secured thereto, a handle embracing and secured to the other end of the bar, a relatively rigid strip initially parallel to the bar and secured to said terminal element, said strip having an arcuate slot toward the handle end, an adjustable contact element movable along said slot, a fixed contact element secured to the bar and engageable with the adjustable contact upon bar bending, an electric vibrator in said handle in circuit with said contacts, and an electric power supply plug in the handle end.

2. A torque metering wrench comprising an elastic bar of uniform cross section, a terminal element embracing one end of the bar and secured thereto, a handle embracing and secured to the other end of the bar, a relatively rigid strip initially parallel to the bar and secured to said terminal element, said strip having an arcuate slot toward the handle end, an adjustable contact element movable along said slot but securable at a desired position to the strip, a fixed contact element secured to the bar and engageable with the adjustable contact upon bar bending, a solenoid in said handle in circuit with

said contacts, and a vibrating armature actuated by said solenoid when energized, said armature having an element for tapping contact with the handle to apprise the operator that predetermined torque has been applied.

3. A torque metering wrench comprising an elastic bar of uniform cross section, a terminal element embracing one end of the bar and secured thereto, a handle embracing and secured to the other end of the bar, a relatively rigid strip initially parallel to the bar and secured to said terminal element, said strip having an arcuate slot toward the handle end, an adjustable contact element movable along said slot, a fixed contact element secured to the bar and engageable with the adjustable contact upon bar bending, a solenoid in said handle in circuit with said contacts, and a vibrating armature actuated by said solenoid when energized, said armature having an element for tapping contact with the handle to apprise the operator that predetermined torque has been applied, said tapping armature being so oriented in the handle as to apply a vibrating force in the plane of action of the wrench to assist in seating nuts or other devices to which torque is applied.

4. A torque metering wrench including an operating handle and elements relatively movable in proportion to the torque applied, a vibrator in said handle, adjustable electric contacts on said relatively movable elements, and a circuit including the contacts and vibrator whereby the latter is energized by contact engagement to afford a tactile indication when a desired torque is applied on the wrench, said vibrator being so oriented as to vibrate the wrench in its plane of action to assist in seating work to which the wrench is applied.

5. In a torque indicating wrench, a work end having an elastic member and a rigid member extending therefrom in substantial parallelism therewith, one member including a substantially arcuate guideway, a contactor adjustably secured to the guideway, another contactor on the other member, said contactors being engageable over a selected narrow range of deflection as one member is deflected relative to the other upon torque application to the elastic member, said contactors being disengaged from one another upon torque application less than or greater than that necessary to cause the contactors to meet in said narrow range of deflection, electric signalling means actuated by engagement of said contacts, and a hollow handle on the end of the elastic member within which said signalling means is disposed.

AUGUST BRUNELLE.
